UNITED STATES PATENT OFFICE

ERNEST L. BYFIELD, OF CHICAGO, ILLINOIS

DESIGN FOR A BOTTLE

Application filed August 30, 1930. Serial No. 36,830. Term of patent 14 years.

To all whom it may concern:

Be it known that I, ERNEST L. BYFIELD, a citizen of the United States, residing at Chicago, in the county of Cook, and State of Illinois, have invented a new, original, and ornamental Design for Bottles, of which the following is a specification, reference being had to the accompanying drawing, forming part thereof.

The figure is a side elevational view of a bottle, showing my new design.

I claim:

The ornamental design for a bottle, as shown.

In testimony whereof I affix my signature.

ERNEST L. BYFIELD.
